PAPERBOARD CARTON

Raymond T. Maston, Jr., Larchmont, N. Y., assignor to National Folding Box Company, New Haven, Conn., a corporation of New Jersey

Application November 21, 1941, Serial No. 419,923

12 Claims. (Cl. 229—6)

This invention relates to paperboard cartons, and more particularly to paperboard cartons designed for the packaging of radio tubes, electric light bulbs, and like fragile articles, constructed to prevent unauthorized removal of the packaged article without leaving visible evidence of tampering and yet permit free and ready inspection of the article packaged therein.

An important object of this invention is to provide a carton especially adapted for the packaging of radio tubes, electric light bulbs, and like fragile articles, which is so designed and constructed as to permit packaging of such articles having various sizes and shapes in the same size carton.

The carton generally comprises an outer tubular sleeve formed from a single blank of paperboard material which is folded into tubular form to provide a sleeve having a generally square or rectangular cross-section. The invention is mainly directed to the construction of the inner tube-supporting member which is telescoped within and secured to the outer tubular sleeve.

The inner tube-supporting member is formed from a single strip of paperboard material which is cut and scored to provide a tube-supporting platform having a suitably shaped aperture therein through which the test end of the tube or bulb may extend. A pair of side wall sections are hinged to the tube-supporting platform section and are arranged in opposed relationship so as to extend along opposite sides of the tube or bulb. One of the side wall sections has a top section hinged to the upper end thereof. The top section has an elongated aperture into which the head end of the tube or bulb may project. The elongated aperture defines a pair of spaced strap portions which are designed to seat against opposite sides of the head end of the tube or bulb so as to frictionally grip and center the same within the inner tube-supporting member.

A downturned flap section is connected to the spaced strap portions, which is arranged adjacent one of the side wall sections. This flap section is provided with a locking tongue extending from the lower end thereof which is adapted to be threaded through a transverse slit provided in the adjacent side wall section. The locking tongue may be drawn through this transverse slit until the strap portions firmly seat against the head end of the tube or bulb so as to firmly retain the tube or bulb in seating position on the platform section and prevent movement of the tube or bulb within the inner tube-supporting member. The projecting end of the locking tongue is folded to lie against the outside face of the side wall section through which it is threaded. When the inner tube-supporting member is positioned within the outer tubular sleeve, the projecting end of the locking tongue is sandwiched

between the side wall section of the inner tube-supporting member and the adjacent side wall panel of the outer tubular sleeve so as to firmly retain the locking tongue in its locked position. As thus assembled the strap portions are held firmly seated against the head end of the tube or bulb with the lower end of the tube or bulb firmly seated on the platform section.

The inner tube-supporting member will retain tubes or bulbs of various shapes, sizes and lengths firmly locked within the inner tube-supporting member and firmly held in spaced relationship from the side wall panels of the outer tubular sleeve. The article is thus protected from damage or injury as a result of exterior blows or jars which may be delivered to the carton.

In one form of the invention the inner tube-supporting member is permanently secured to the outer tubular sleeve by means of a tongue which is struck out from one of the side wall sections of the outer tubular sleeve. This tab is permanently secured to the adjacent side wall panel of the outer tubular sleeve by a suitable staple or rivet so that the inner tube-supporting member and its packaged tube or bulb cannot be removed from the outer tubular sleeve without leaving visible evidence of tampering. In this form of the invention one of the side wall sections of the inner tube-supporting member may be provided with a closure section hinged thereto which serves to close the adjacent end of the outer tubular sleeve.

In another form of the invention a connecting strip formed of paperboard material may be provided, which strip has a hook portion extending through an elongated vertical slit in one of the side wall sections of the inner tube-supporting member. This connecting strip may be stapled or riveted to the adjacent side wall panel of the outer tubular sleeve so as to permanently retain the inner tube-supporting member within the outer sleeve and yet permit sliding or telescoping movement of the inner tube-supporting member within the outer tubular sleeve so that the test end of the tube or bulb may be projected for test purposes. In this form of the invention the connecting strip may be provided with a closure section to close the adjacent end of the outer tubular sleeve.

An object of this invention is to provide an improved carton for radio tubes, bulbs and like fragile articles, which is so constructed that the same size carton may be used for the packaging of various fragile articles of different sizes, shapes and lengths.

Another object of this invention is to provide an improved carton for fragile articles, having associated therewith an inner tube-supporting member so constructed that it may be adjusted as to length so as to accommodate articles of various shapes, sizes and lengths, and which will

firmly retain the article in spaced relationship from the side wall panel of the outer enclosing sleeve of the carton.

Various other features and advantages of the invention will be apparent from the following particular description and from an inspection of the accompanying drawings.

Although the novel features which are believed to be characteristic of this invention will be particularly pointed out in the claims appended hereto, the invention itself, as to its objects and advantages and the manner in which it may be carried out, may be better understood by referring to the following description taken in connection with the accompanying drawings forming a part thereof, in which:

Fig. 1 is a plan view of a paperboard blank which has been cut and scored to provide the outer tubular sleeve for the carton;

Fig. 2 is a plan view of a prepared blank which has been cut and scored to form the inner tube support;

Fig. 3 is a fragmentary perspective view of the outer tubular sleeve assembled from the blank shown in Fig. 1;

Fig. 4 is a perspective view of the inner tube-supporting member as it appears when wrapped around a radio tube ready for insertion into the outer tubular sleeve;

Fig. 5 is a perspective view of the fully assembled and packed carton, certain parts being broken away to illustrate structural details;

Fig. 6 is a vertical cross-sectional view through the packed carton as it appears when looking in the direction of the arrows 6-6 of Fig. 5;

Fig. 7 is a perspective view of an inner tube-supporting member of modified construction partially wrapped around a radio tube, this view also showing a connecting strip associated with the inner tube-supporting member for adjustably retaining the inner tube-supporting member within the outer tubular sleeve;

Fig. 8 is a perspective view of the outer tubular sleeve ready to receive the inner tube-supporting member and connecting strip shown in Fig. 7;

Fig. 9 is a perspective view of the fully packed carton assembled from the parts shown in Figs. 7 and 8 as it appears when the test end of the tube has been ejected for test purposes; and

Fig. 10 is a vertical cross-sectional view through the packed carton shown in Fig. 10 with the test end of the tube retracted, this view being taken along line 10-10 of Fig. 9.

Similar reference characters refer to similar parts throughout the several views of the drawings and the specification.

The radio tube carton as illustrated in Figs. 5 and 6 is generally formed from a substantially rectangular blank A of paperboard material which has been cut and scored as indicated in Fig. 1 to form the outer sleeve of the carton. The inner tube-supporting member B, as shown in Fig. 2, comprises generally a strip of paperboard material suitably cut and scored so that when wrapped around the tube or bulb it may be inserted with the tube or bulb into the outer tubular sleeve. The sleeve-forming blanks A may be cut from large sheets or rolls of suitable paperboard material, substantially without waste of material, the sleeve-forming blanks being adapted to be cut and scored on an automatic cutting and scoring machine at a high production rate. The inner tube-supporting members B are cut from large sheets or rolls of paperboard mate-

rial which are first imprinted. The inner tube-supporting member is so folded and assembled around the tube or bulb that the strip need be imprinted on one side thereof only.

5 The sleeve-forming blank A comprises four side wall-forming panels 1, 2, 3 and 4, which are joined along their side edges by fold lines 6. A securing flap 5 is hinged to one of the side wall panels 4 along fold line 6 and receives adhesive for securing the same to the free side edge of the side wall panel 1. Opposite side wall panels 1 and 3 are each provided with a top flap 7 hinged thereto along a fold line 8, which may be turned inwardly to form a support for the inner tube-supporting member, as will hereinafter appear. The blanks A when assembled and glued into tubular form may be shipped in flat collapsed condition and so stored until ready for use.

The inner tube-supporting member B comprises 20 generally a tube-supporting partition or platform 10 upon which the lower end of the tube or bulb is adapted to rest. A suitable opening or aperture 11 is provided in the platform 10 through which the test end or prongs p of the tube or bulb 25 may project, as shown more particularly in Figs. 4 and 6. A side wall section 13 is hinged to the platform section 10 along a fold line 14 and an oppositely disposed side wall section 12 is hinged to the opposite side edge of the platform 10 along 30 a fold line 14. In assembling the inner tube-supporting member around the tube, the tube is first placed upon the platform section 10 and then the side wall sections 13 and 14 are raised to extend upwardly along opposite sides of the tube, 35 as shown more particularly in Fig. 4.

A top section 15 is hinged to the side wall section 13 along a fold line 16 and is foldable to extend over the top end of the tube. A flap portion 17 is hinged to the top section 15 along a fold 40 line 18 and is arranged to be folded downwardly to lie adjacent the inside face of the side wall section 12. A tongue 19 extends from the downturned flap section 17 and is arranged to be inserted through a transverse slit 20 in the side wall section 12.

45 It will be noted that an elongated aperture 21 is cut lengthwise of the strip through the central portion of the top section 15 and into the upper portions of side wall section 13 and downturned flap section 17. The elongated aperture 21 is so shaped as to receive the head end h of the tube or bulb and defines strap portions 22 on each side of the aperture adapted to rest on opposite sides of the head end h of the tube or bulb. A securing tab 29 may also be cut out from the side wall section 13 and is defined by a transverse cut 30 whose ends join a pair of spaced vertical cuts 31. The tab 29 is hinged to side wall section 13 along a fold line 32. In assembling the inner tube-supporting member around the tube or bulb, the tab portion 29 is bent downwardly, as shown in Fig. 4, and provides a means for permanently securing the inner tube-supporting member to the outer tubular sleeve.

60 A top closure flap 23 is hinged to the upper end of the side wall section 12 along a fold line 24. A tuck-in flap 25 is hinged to the opposite edge of the closure section 23 along a fold line 26. A customer's tab 27 is removably connected to the opposite edge of the tuck-in flap 25 by a line of perforations 28. The customer's tab 27 is so designed that it may be inserted through a transverse slit 9 provided in the adjacent side wall panel 2 of the outer tubular sleeve.

65 70 75 In assembling the inner tube-supporting mem-

ber B around the bulb or tube T, the bottom end of the bulb or tube is positioned to seat upon the platform section 10 with the test end or prongs p of the tube or bulb extending through the aperture 11 provided therein. Side wall sections 12 and 13 are then raised substantially at right angles to the platform section 10 so as to extend along opposite sides of the tube or bulb. The top section 15 is then folded over the top of the tube or bulb so that the head end h of the tube or bulb will center itself within the elongated aperture 21. The strap portions 22 rest against opposite sides of the top end of the tube or bulb to retain the tube or bulb properly centered within the folded strip. Flap section 17 is then folded downwardly and the tongue 19 threaded through the slit 20 in the side wall section 12. The insert tongue 19 is then pulled down so that the strap portions 22 firmly seat against the head end of the bulb. The protruding end of the inserted tongue 19 is then bent upwardly, as shown more particularly in Fig. 6. When the insert tongue 19 has been thus folded, the tube or bulb is firmly seated between the platform section 10 and the strap portions 22 and is held substantially immovable between the side wall sections 12 and 13.

The inner tube-supporting member thus wrapped around the tube or bulb, as above described and illustrated more particularly in Fig. 4, is then telescoped into the assembled outer tubular sleeve, as shown in Fig. 3, to the point where the fold line 24 of the inner tube-supporting member is substantially co-planar with the upper edge of the adjacent side wall panel 4 of the outer sleeve. The supporting flaps 7 of the outer sleeve are then turned inwardly, as shown in Fig. 3, and the top closure section 23 is folded down so as to overlie the turned supporting flaps 7. The tuck-in flap 25 is inserted into the carton and the customer's tab 27 is threaded through the elongated slit 9 in the adjacent side wall panel 2, as shown more particularly in Figs. 5 and 6. The tuck-in flap 25 is so proportioned that when the closure section 23 is in closed position, as shown in Fig. 5, the line of perforations 26 is adjacent the transverse slit 9, so that the customer's tab 27 may be easily removed by the merchant and retained for record purposes. The downturned securing tab 29 is then permanently secured to the side wall panel 2 of the outer tubular sleeve by a staple or rivet 33 or other permanent securing means. When the tube or bulb has thus been packed it cannot be removed from the carton without leaving visible evidence of tampering. It will also be noted that the upturned insert tongue 19 is sandwiched between the side wall section 12 of the inner tube-supporting member and the adjacent side wall panel 4 of the outer sleeve so that it cannot loosen. The tab 29 may be provided with one or more transverse score lines 32', as shown in Figs. 2 and 4, so that the portions 29' therebetween are free to fold inwardly and downwardly so as to permit test ejection of the prongs p of the tube by merely exerting a pushing pressure on the head end h of the bulb.

It will now be appreciated that the inner tube-supporting member B of a given size will firmly hold and retain tubes or bulbs of various sizes and shapes and which vary in length one-half inch or more. The strap portions 22 adjust themselves to the shape and contour of the upper end of the tube or bulb so as to hold the tube or bulb properly centered within the inner tube-supporting member and spaced from the side

wall panels of the outer tubular sleeve. The strap portions 22 are so formed as to grip the upper ends of tubes or bulbs of various sizes and shapes, and when the tongue 19 is inserted through the friction slit 20 and upturned, the strap portions 22 will press the lower end of the tube or bulb into firm seating engagement against the platform section 10. The upturned tongue 19 is frictionally held between the side wall section 12 of the inner tube-supporting member and the adjacent side wall panel 4 of the outer sleeve so that it cannot slip or loosen. Since the lower end of the downturned securing tab 29 extends substantially to the lower edge of the side wall panel 2 of the outer tubular sleeve, the securing rivet 33 can be easily and quickly applied without interference from adjacent parts of the tube or carton. The tube or bulb is thus permanently sealed within the carton so that it cannot be removed and a used or defective tube or bulb substituted without leaving visible evidence of tampering. The upper end of the tube or bulb is easily accessible for inspection by simply lifting the closure section 23. The tube or bulb may be tested in its housed position within the carton by simply inserting the test end or prongs p of the tube in a raised test socket. If the tab 29 is provided with the transverse fold lines 32' the prongs p may be projected beyond the lower edge of the outer shell A for insertion into a flat test socket by opening closure flap 23 and exerting pressure on the head end h of the bulb. The intermediate portions 29' of the tab 29 will thus execute an inward and downward rolling and folding action.

There is illustrated in Figs. 7 to 10 inclusive a carton adapted for the packaging of radio tubes, bulbs and like fragile articles, of somewhat modified construction. The outer tubular sleeve A which forms a part of this carton may be constructed from a blank similar to that shown in Fig. 1 and need not be further described.

The inner tube-supporting member B', illustrated in Fig. 7, is formed from a single strip of paperboard material and in many respects is similar to the inner tube-supporting member B illustrated in Fig. 2. The inner tube-supporting member B' comprises a platform section 10 having an aperture 11 therein through which the test end of the tube or bulb extends. Opposed side wall sections 12 and 13 are hinged to opposite side edges of the platform section 10. A top section 15 is hinged to the upper end of the side wall section 13 and a downturned flap section 17 is hinged to the top section 15. The outer end of the flap section 17 is provided with a locking tongue 19 which is adapted to be inserted through the transverse slit 20 in the side wall section 12. The inner tube-supporting member B' is also provided with an elongated aperture 21 which extends through the mid-portion of the top section 15 and into the upper end portion of the side wall section 13 and downturned flap section 17, so as to define strap portions 22 adapted to seat against the head end h of the tube or bulb.

It will be noted that the side wall section 12 of the tube-supporting member B' does not carry the top closure section 23 which is characteristic of the inner tube-supporting member B shown in Fig. 2. A top closure section, however, is provided but it is formed as a part of a connecting strip C which has a sliding engagement with the side wall section 13 of the inner tube-supporting member. The connecting strip C is provided with

a leg portion 40 whose lower end is formed to provide a hook portion 41 which is adapted to be inserted through a vertical slit 42 cut in the side wall section 13 of the inner tube-supporting member. When thus connected the inner tube-supporting member has a limited vertical sliding movement with respect to the leg portion 40. The top closure section 43 is hinged to the upper end of the leg portion 40 along a fold line 44. A tuck-in flap 45 is hinged to the closure section 43 along a fold line 46 and the customer's tab 47 is connected to the opposite edge of the tuck-in flap 45 by a line of perforations 48. The platform section 10 is also provided with a pair of opposed laterally extending flaps 35 hinged thereto along fold lines 36, which provide supporting legs for the inner member B' and its enclosed tube or bulb.

In assembling tubes or bulbs in the carton shown in Figs. 7 to 10 inclusive, the lower end of the tube or bulb T is positioned upon the platform section 10, with the test prongs p thereof inserted through the aperture 11. The side wall sections 12 and 13 are folded substantially at right angles to the platform section 10 and the top section 15 is folded over the head end h of the tube or bulb so that the strap portions 22 rest on opposite sides of the head end of the tube or bulb with the center portion of the head end extending into the elongated aperture 21. The flap section 17 is folded downwardly and the locking tongue 19 inserted through the slit 20 in the side wall section 11. The projecting end of the locking tongue 19 is then folded upwardly to prevent withdrawal thereof and to retain the strap portions 22 in firm seating engagement against the head end h of the tube or bulb. The connecting strip C is applied to the inner tube-supporting member B' by inserting the hook portion 41 thereof through the vertical slit 42 in the side wall section 13. The leg portion 40 of connecting strip C will then be positioned against the outside face of the side wall section 13. The tube or bulb thus wrapped within the inner tube-supporting member B' and with the connecting strip C thus attached is telescoped into the outer tubular sleeve A. The laterally extending flap portions 35 are folded downwardly so as to lie against the inside face of the adjacent side wall panels 1 and 3 of the outer tubular sleeve. The leg portion 40 of the connecting strip C is positioned to lie against the inside face of the side wall panel 4 of the outer tubular sleeve and is so arranged that the fold line 44 will be substantially co-planar with the upper edge of the adjacent side wall panel 4, as shown more particularly in Fig. 10. A sealing staple or rivet 50 is applied in a manner to secure the upper end of the leg portion 40 of the connecting strip C to the adjacent side wall panel 4 of the outer tubular sleeve. This operation can be readily performed without obstruction. The supporting flaps 7 of the outer tubular sleeve are then turned inwardly and the closure section 43 is folded to overlie the inturned flaps 7. The tuck-in flap 45 is then inserted into the carton, and the customer's tab 47 is threaded through the slit 9 provided in the side wall panel 2 of the outer tubular sleeve.

When the inner tube-supporting member B' is thus arranged within the outer tubular sleeve, the lower ends of the supporting legs 35 will be substantially flush with the lower ends of the adjacent side wall panels 1 and 3 of the outer tubular sleeve. The legs 35 are of sufficient length

so that the lower end of the socket prongs p of the tube T will be raised as shown in Fig. 10 and will not rest against the shelf or surface upon which the carton is positioned. However, when the packed carton is held in the hand, the prongs p may be readily grasped to telescope the inner tube-supporting member within the outer tubular sleeve to such an extent as to extend the prongs p beyond the lower ends of the side wall panels of the outer tubular sleeve as shown in Fig. 9. The prongs p may be projected a distance which is limited by the length of the elongated slit 42 provided in the side wall section 13 of the inner tube-supporting member. The leg portions 35 may then be flared outwardly, as shown in Fig. 9, to permit insertion of the test prongs p into either a flat or raised test socket. The tube or bulb may be readily inspected by swinging open the closure section 43. The carton is so constructed as to permit ready inspection and testing of the tube or bulb and yet prevent tube or bulb removal or substitution without leaving visible evidence of tampering, since the tube or bulb cannot be removed from the packed carton 25 without visibly tearing or lacerating the carton.

The carton construction illustrated in Figs. 1 to 6 inclusive may be constructed so that the inner tube-supporting member and its contained tube or bulb has a limited telescoping movement 30 within the outer tubular sleeve when assembled therein by the provision of transverse fold lines 32' in the tab 29 so that the test end of the tube may be projected beyond the lower end of the outer tubular sleeve and thus permit insertion 35 thereof into a flat test socket. The carton illustrated in Figs. 7 to 10 inclusive is also so constructed as to permit a limited telescoping movement of the inner tube-supporting member and its contained tube or bulb within the outer tubular sleeve to permit test ejection of the prongs p for insertion into a flat test socket. The inner tube-supporting member of both constructions 40 permit adjustment thereof to accommodate tubes or bulbs of varying sizes and lengths. Both constructions are also provided with strap portions 45 so shaped and formed as to engage the head end of a tube or bulb of almost any shape. The inner tube-supporting member is wrapped around the tube or bulb and firmly retains the tube or bulb thereon, so that the tube or bulb is frictionally and firmly retained in spaced relationship 50 from the side wall panels of the outer enclosing sleeve A.

It will now be appreciated that the same size outer tubular sleeve A and the same size inner tube-supporting members B and B' may be used to package tubes and bulbs of various lengths, sizes and shapes. It will be noted, by referring to Figs. 6 and 10, that there is substantial clearance between the head end h of the tube or bulb and the top closure section, so that the length of the tube or bulb may be substantially extended and still have its head end h spaced from the top closure section a sufficient distance to properly 60 protect the head end of the tube or bulb. It will be further noted that the locking tongue 19 is of considerable length so that it may extend through the slit 20 at almost any point along its length. The upturned end of the locking tongue 19 is sandwiched between the side wall section 12 of the inner tube-supporting member and the adjacent side wall panel of the outer tubular sleeve so that it cannot slip from its locked position.

The blank which forms the outer tubular sleeve 70 and the blank which forms the inner tube-sup-

porting member may be economically manufactured at a high production rate on automatic machinery without hand operation. The packaging operation may be quickly and economically performed. The packed carton provides an attractive package which is strong and sturdy and protects the fragile contents from damage and breakage.

While certain novel features of the invention have been disclosed and are pointed out in the annexed claims, it will be understood that various omissions, substitutions and changes may be made by those skilled in the art without departing from the spirit of the invention.

What is claimed is:

1. A carton for radio tubes, bulbs and like fragile articles including in combination, an outer tubular sleeve having enclosing side wall panels, an inner tube-supporting member having a tube-supporting platform section, opposed side wall sections connecting said platform, one of said side wall sections having a transverse friction slit positioned between the ends thereof, a top section hinged to the other of said side wall sections and provided with an elongated aperture therein adapted to adjust itself to receive the head end of the article, a locking tongue connected to said top section threadable through said slit in the adjacent side wall section and having a projecting end portion rebent upon itself and sandwiched between said last-named side wall section and the adjacent side wall panel of the outer tubular sleeve, and means for securing said inner tube-supporting member to said outer tubular sleeve.

2. A carton for radio tubes, bulbs and like fragile articles including in combination, an outer tubular sleeve having enclosing side wall panels, an inner tube-supporting member having a tube-supporting platform section, opposed side wall sections connecting said platform one of said side wall sections having a transverse friction slit positioned between the ends thereof, a top section hinged to the other of said side wall sections and provided with an elongated aperture therein adapted to adjust itself to receive the head end of the article, a locking tongue connected to said top section having an end portion thereof projecting through said friction slit in the adjacent side wall section, said projecting end being rebent upon itself and sandwiched between said last-named side wall section and the adjacent side wall panel of the outer tubular sleeve, and means for securing said inner tube-supporting member to said outer tubular sleeve.

3. A carton for radio tubes, bulbs and like fragile articles including in combination, an outer tubular sleeve having enclosing side wall panels, an inner tube-supporting member having a tube-supporting platform section, opposed side wall sections hinged to said tube-supporting platform, spaced strap portions connected to one of said side wall sections defining an elongated aperture therebetween adapted to adjust itself to receive the head end of the tube or bulb, a locking tongue connected to said strap portions, a transverse slit in the other side wall section through which said locking tongue is adapted to be drawn therethrough a distance sufficient to draw said strap portions into snug engagement with the head end of the tube or bulb, the outer end portion of said locking tongue being rebent to lie against the outside face of said last-named side wall section and against the inside face of the adjacent side wall panel of the outer tubular sleeve, and means for

connecting said inner tube-supporting member to said outer tubular sleeve.

4. A carton for radio tubes, bulbs and like fragile articles including in combination, an outer tubular sleeve having enclosing side wall panels, an inner tube-supporting member having a tube-supporting platform section, opposed side wall sections connecting said platform, a top section hinged to one of said side wall sections and provided with an elongated aperture therein adapted to adjustably receive the head end of the article, a tongue hinged to said top section threaded through a transverse friction slit in the other side wall section providing an adjustable connection between said side wall sections, said tongue having an end portion rebent upon itself and sandwiched between said other side wall section and the adjacent side wall panel of the outer sleeve, a rebent tab cut from one of said side wall sections and positioned adjacent a side wall panel of said outer sleeve, and a sealing element for permanently securing said tab to said adjacent side wall panel.

5. A carton for radio tubes, bulbs and like fragile articles including in combination, an outer tubular sleeve having enclosing side wall panels, an inner tube-supporting member having a tube-supporting platform section, opposed side wall sections connecting said platform, a top section hinged to one of said side wall sections and provided with an elongated aperture therein adapted to adjustably receive the head end of the article, a tongue hinged to said top section and threaded through a transverse friction slit in the other side wall section providing an adjustable connection between said side wall sections, said tongue having an end portion rebent upon itself and sandwiched between said other side wall section and the adjacent side wall panel of the outer sleeve, and means for securing said inner tube-supporting member to said outer tubular sleeve, said means including a connecting strip having a leg portion positioned between one of said side wall sections and the adjacent side wall panel, an elongated slit in said last-named side wall section, a hook portion associated with said leg portion extending into said slit, and a sealing element for permanently securing said leg portion to said adjacent side wall panel.

6. A carton for radio tubes, bulbs and like fragile articles including in combination, an outer tubular sleeve having enclosing side wall panels, an inner tube-supporting member having a tube-supporting platform section, opposed side wall sections connecting said platform, a top section hinged to one of said side wall sections and provided with an elongated aperture therein adapted to adjustably receive the head end of the article, a tongue hinged to said top section threaded through a transverse friction slit in the other side wall section providing an adjustable connection between said side wall sections, said tongue having an end portion rebent upon itself and sandwiched between said other side wall section and the adjacent side wall panel of the outer sleeve, and means for securing said inner tube-supporting member to said outer tubular sleeve, said means including a connecting strip having a leg portion positioned between one of said side wall sections and the adjacent side wall panel, an elongated slit in said last-named side wall section, a hook portion associated with said leg portion extending into said slit, and a sealing element for permanently securing said leg portion to said adjacent side wall panel, and a closure section

hinged to said leg portion adapted to close the adjacent end of the outer tubular sleeve.

7. A carton for radio tubes, bulbs and like fragile articles including in combination, an outer tubular sleeve having enclosing side wall panels, an inner tube-supporting member having a tube-supporting platform section, opposed side wall sections hinged to said tube-supporting platform, spaced strap portions connected to one of said side wall sections defining an elongated aperture therebetween adapted to receive the head end of the bulb or tube, a locking tongue connected to said strap portion, a transverse slit in the other side wall section through which said locking tongue is adapted to be inserted, the outer end portion of said locking tongue being rebent to lie against the outside face of said last-named side wall section and against the inside face of the adjacent side wall panel of the outer tubular sleeve, a closure section hinged to said last-named side wall section adapted to close the adjacent end of the outer tubular sleeve, and means for connecting said inner tube-supporting member to said outer tubular sleeve.

8. A carton for radio tubes, bulbs and like fragile articles including in combination, an outer tubular sleeve having enclosing side wall panels, an inner tube-supporting member having a tube-supporting platform section, opposed side wall sections hinged to said tube-supporting platform, spaced strap portions connected to one of said side wall sections defining an elongated aperture therebetween adapted to receive the head end of the tube or bulb, a locking tongue connected to said strap portions, a transverse slit in the other side wall section through which said locking tongue is adapted to be inserted, the outer end portion of said locking tongue being rebent to lie against the outside face of said last-named side wall section and against the inside face of the adjacent side wall panel of the outer tubular sleeve, a closure section hinged to said last-named side wall section adapted to close the adjacent end of the outer tubular sleeve, a securing tab hinged to said inner tube-supporting member positioned adjacent a side wall panel of said outer sleeve, a fold line extending transversely across said tab to permit downward folding movement of a portion thereof, and a sealing element for permanently securing said tab to said adjacent side wall panel.

9. A carton for radio tubes, bulbs and like fragile articles including in combination, an outer tubular sleeve having enclosing side wall panels, and an inner tube-supporting member having a tube-supporting platform section, opposed side wall sections hinged to said platform section one of said side wall sections having a transverse friction slit positioned between the ends thereof, strap portions connected to the other of said side wall sections defining an elongated aperture therebetween shaped to receive the upper end of the tube or bulb, a locking tongue extending from said strap portions drawn through said transverse slit a sufficient distance to draw said strap portions into hugging conformity with the upper end of the tube or bulb, the outer end portion of said locking tongue being rebent and frictionally retained between one of said side wall sections of the inner tube-supporting member and the adjacent side wall panel of the outer tubular sleeve, a securing tab connected to one of said side wall sections, and means for securing said securing tab to the adjacent side wall panel of the outer

tubular sleeve which cannot be removed or detached without leaving visible evidence of tampering.

10. A carton for radio tubes, bulbs and like fragile articles including in combination, an outer tubular sleeve having enclosing side wall panels, and an inner tube-supporting member having a tube-supporting platform section, opposed side wall sections hinged to said platform section, strap portions connected to one of said side wall sections defining an elongated aperture therebetween shaped to receive the upper end of the tube or bulb, a tongue extending from said strap portions through a transverse slit provided in the other side wall section, the outer end portion of said tongue being rebent and frictionally retained between one of said side wall sections of the inner tube-supporting member and the adjacent side wall panel of the outer tubular sleeve, and means for securing said inner tube-supporting member to said outer tubular sleeve, said means including a connecting strip having a leg portion positioned between one of said side wall sections and the adjacent side wall panel, an elongated slit in said last-named side wall section, a hook portion associated with said leg portion extending into said slit, and a sealing element for permanently securing said leg portion to said adjacent side wall panel.

11. A carton for radio tubes, bulbs and like fragile articles including in combination, an outer tubular sleeve having enclosing side wall panels, and an inner tube-supporting member having a tube-supporting platform section, opposed side wall sections hinged to said platform section, strap portions connected to one of said side wall sections defining an elongated aperture therebetween shaped to receive the upper end of the tube or bulb, a tongue extending from said strap portions through a transverse slit provided in the other side wall section, the outer end portion of said tongue being rebent and frictionally retained between one of said side wall sections of the inner tube-supporting member and the adjacent side wall panel of the outer tubular sleeve, a connecting strip slidably connected to one of said side wall sections, means for permanently securing said connecting strip to the adjacent side wall panel of the outer tubular sleeve which cannot be detached without leaving visible evidence of tampering, said connecting strip having a closure section for closing the adjacent end of the outer tubular sleeve.

12. A carton for radio tubes, bulbs and like fragile articles including in combination, an outer tubular sleeve having enclosing side wall panels, an inner tube-supporting member having a tube-supporting platform section, opposed side wall sections connecting said platform, a top section hinged to one of said side wall sections and provided with an elongated aperture therein adapted to adjust itself to receive the head end of the article, a tongue hinged to said top section threadable through a transverse friction slit in the other side wall section providing means for adjustably connecting said tongue to the adjacent side wall section whereby the span between said platform section and said top section may be modified to snugly accommodate the size and shape of the article, said tongue having an end portion rebent upon itself and sandwiched between said other side wall section and the adjacent side wall panel of the outer sleeve.

RAYMOND T. MASTON, JR.
